METAL TOP FOR IRONING BOARDS

Gustave S. Krantz, Milwaukee, Wis., assignor to
Gneider, Paeschke & Frey Co., Milwaukee, Wis.,
a corporation of Wisconsin

Application December 9, 1947, Serial No. 790,505

1 Claim. (CL. 38—137)

1

This invention relates to improvements in metal tops for ironing boards.

Ironing boards of this character are used with pads of heat-insulating material and if the pads are not ventilated from below steam will be condensed by the metal top and moisten the pad so that proper ironing cannot take place. Tops made of expanded metal and metal tops with circular openings therein have been used in an effort to satisfactorily ventilate the bottom of the pad. However, these methods either weaken the board, necessitate the use of too heavy metal, or provide insufficient ventilation.

It is an object of this invention, therefore, to provide a metal top for ironing boards which is light in weight, inherently strong, and adequately ventilated.

This object is obtained by forming the top from a thin sheet of metal which has depressed from the surface thereof a plurality of ventilating pockets. These pockets, below the top, have lateral openings which permit the unobstructed passage of air or steam. Each pocket is constructed by slitting the metal at spaced places and pressing and drawing the metal between the slits downwardly until the surface of the depressed area lies substantially below the bottom of the sheet of metal. The bottom edge of a slit in the undepressed portion and the top edge of such slit in the depressed portion define an opening which is below the top and is lateral of the pocket. The drawn portion of the sheet of metal defines the wall of the pocket, places the sheet under an internal stress, and also provides a short strengthening rib. By spacing the pockets in a row extending longitudinally of the top with the slits substantially perpendicular to the longitudinal axis of the row, the stiffening action of the ribs is made effective to resist longitudinal bending of the board. This action is increased and adequate ventilation assured by providing a number of such rows spaced over the width of the board. While the pockets of each row are shown in alignment across the board, this is not essential. The pockets of one row may be staggered with respect to the pockets of other rows. The staggering will not affect the inherent tension placed in the metal top by the forming of the pockets. Although an important result of the construction of the ventilating pockets is to reenforce and strengthen the metal top, the principal attribute is the providing of a chamber below the upper surface of the board which is ventilated through lateral openings. The surface area of each pocket is so small that in normal

2

ironing conditions, that portion of the insulating pad which overlies the pocket will be depressed into the pocket only a slight amount. This will not in any way obstruct such lateral openings. After the weight of the iron has been removed from over a pocket, the portion of the pad which has been depressed therein will rise. This creates a breathing action in each pocket over which ironing takes place. Some of the steam and air is thus impelled and fresh air brought into the pocket to positively ventilate the board and the insulating pad.

The novel features, which are considered characteristic of the invention, are set forth with particularity in the appended claim. The invention itself, however, both as to its organization and its method of operation, together with additional objects and advantages thereof, will best be understood from the following description of a specific embodiment when read in connection with the accompanying drawings, in which:

Fig. 1 is a view in side elevation of an ironing board embodying the present invention;

Fig. 2 is a slightly enlarged plan view of the metal top for the ironing board embodying the present invention;

Fig. 3 is an enlarged sectional view taken on the line 3—3 of Fig. 1;

Fig. 4 is a fragmentary sectional view taken on the line 4—4 of Fig. 3; and

Fig. 5 is a greatly enlarged fragmentary perspective view of one of the pockets comprising an element of this invention.

Referring to the drawings by reference numerals, the ironing board consists of a top, indicated generally at 10, supported on conventional foldable legs indicated generally at 11. The top 10, as indicated in Fig. 2, has the usual shape. It is formed from a thin sheet of metal and has a peripheral depending flange 12 ending in a rolled-in stiffening bead 13. Near the head end, at the intermediate section and near the foot end, there are provided laterally extending braces designated respectively 14, 15, and 15a. These braces, as shown in Figs. 3 and 4, may each have several longitudinally extending strengthening ribs 16. The tops of the ribs are flush with the bottom of the top 10 to provide additional support. The ends of each brace are spot welded to the flanges 12 through the medium of tangs 17 or the like formed thereon to hold the braces in place and rigidly tie the unit together. As shown in Fig. 1 the leg structure 11 is mounted to the braces 14 and 15, respectively, in the conventional manner.

The essential element of this invention resides in the manner in which the thin sheet metal 18 providing the top 10 is formed. The sheet 18 is provided with a multiplicity of ventilating pockets indicated generally at 19. Each pocket is constructed by providing the metal sheet 18 with a pair of spaced slits 20 extending laterally of the board and pressing and drawing the metal between the slits downwardly until the surface 21 of the depressed area lies substantially (approximately one-eighth of an inch) below the bottom of the sheet 18. The drawn sloping portions 22 define the ends of each pocket while the bottom edge of each slit 20 in the undepressed sheet 18 and the top edge of the slit 20 in the depressed portion 21 define lateral ventilating openings 23.

The pockets 19 are spaced in rows extending longitudinally of the top 10, such rows being respectively indicated by the numeral 24. It has been found that seven such rows equally spaced with the pockets in each row spaced at substantially one inch centers provides a sufficient number of pockets to properly ventilate the under surface of an insulating pad placed on the ironing board top.

Each of the drawn portions 22 form a short top reinforcing rib. These ribs, being in substantial longitudinal alignment and closely spaced along the length of the board, cooperate with the flanges 12 to brace the board against deflection longitudinally. In the pressing and drawing of each pocket, the sheet metal top 18 is provided with an internal stress which also tends to tighten and thus stiffen the surface of the board.

Each pocket is substantially one-quarter inch wide by one-half inch long and the surface area thus defined is so small that in normal ironing conditions that portion of an insulating pad overlying the pocket will be depressed into the pocket only a slight amount. Such slight depressing of a portion of the pad will not in any way obstruct the lateral openings 23. However, the alternate depressing of a small portion of the pad into the pocket and its later withdrawal upon removal of the iron from over the pocket creates a breathing action in the various pockets as the iron passes over the surface of the pad. This action impels some of the steam and moist air present in the pocket and thereafter causes fresh air to be drawn into the pocket

under atmospheric pressure. This action greatly increases the effective ventilation of the board and the bottom of the pad without any unnecessary weakening of the structural strength of the board or necessitating the use of unduly heavy metal sections in the top.

Although only one embodiment of the invention is shown and described herein, it will be understood that this application is intended to cover such changes or modifications as come within the spirit of the invention or scope of the following claim.

I claim:

A light-weight, strong and ventilated top for an ironing board, said top having a longitudinal axis longer than the transverse axis thereof and comprising a thin sheet of metal having a plurality of pairs of spaced slits therethrough, each of said slits being substantially perpendicular to said longitudinal axis, said pairs of slits being arranged in spaced parallel rows extending longitudinally of said top, a portion of the metal between said slits being deposited below the bottom of said sheet to define lateral ventilating openings communicating with the top of said sheet, other portions of the metal between said slits sloping from said portion below the bottom of said sheet to the level of said sheet to define below said sheet reinforcing ribs arranged in longitudinal alignment to aid in bracing said top against deflection longitudinally, said openings affording ventilation for ironing pads placed on said top without lessening the strength of said sheet by the removal of part thereof to form ventilating openings therein.
